UNITED STATES PATENT OFFICE.

FREDERICK S. CROSSLEY AND FREDERICK W. CROSSLEY, OF BLACKROCK, DUBLIN,
IRELAND.

SECTIONAL HULL CONSTRUCTION.

1,418,629.

Specification of Letters Patent. Patented June 6, 1922.

Application filed February 3, 1922. Serial No. 533,778.

To all whom it may concern:

Be it known that we, FREDERICK SAMUEL CROSSLEY, a subject of the King of Great Britain, residing in Blackrock, Dublin, Ireland, and FREDERICK WILLIAM CROSSLEY, a subject of the King of Great Britain, residing in Blackrock, Dublin, Ireland, have invented certain new and useful Improvements in Sectional Hull Constructions, of 10 which the following is a specification.

This invention relates to the construction of the hulls of boats, barges or other vessels and whilst particularly adapted for boats or vessels of the so-called "welded" type 15 may also be used with boats or vessels in which the plates are bolted or riveted together.

The present invention has for its object certain improvements designed not only to 20 reduce the cost of construction but to enable the construction to be carried out more expeditiously than with the present systems of construction.

Boats or vessels constructed according to 25 this invention, moreover, possess the advantage that a considerably increased carrying capacity may be secured as compared with vessels of the same draught of ordinary construction, together with a greater 30 cubic capacity.

With a vessel constructed according to 35 this invention when the plating has been assembled and welded or otherwise connected the structure so produced is of much greater strength than with ordinary systems of welded construction.

According to this invention instead of 40 the usual frame or ribs, to which the plates are secured, plates are employed which may be of rectangular or other outline having flanges upon all sides said flanges, when the plates are assembled, being welded or otherwise connected, replacing the usual ribs.

In order that the invention may be better understood drawings are appended in 45 which:—

Fig. 1 is a perspective view showing one form of plate according to this invention.

Fig. 2 is a perspective view showing four 50 of the plates for the bow.

Fig. 3 is a similar view showing three of the stern plates.

Fig. 4 is a perspective view showing a form of plate whereby the beam of the vessel may be increased. 55

Fig. 5 is a perspective view showing an alternative form of plate.

Fig. 6 is a plan showing the arrangement of plates shown in Fig. 5 when assembled.

Fig. 7 is a perspective view showing a 60 modified form of plate to that shown in Fig. 5.

Fig. 8 is a plan showing plates according to Fig. 7 assembled.

Fig. 9 is a perspective view showing a 65 further modification.

Fig. 10 is a plan showing a number of plates such as shown in Fig. 9 assembled.

Fig. 11 is a perspective view showing a means for strengthening the keelson. 70

Fig. 12 is a view showing a modified form of plate embodying the keelson.

Referring to Figs. 1 to 3 of the accompanying drawings *a* indicates generally sections formed of sheet metal each of such 75 length as to extend from the keel to the deck and provided upon their sides and bottom with inwardly turned flanges *a*¹. The upper edge of the plate is turned over as shown at *a*² and then downwardly as at 80

*a*³, a horizontal flange being formed at *a*⁴, the flange *a*⁴ when the plates are assembled, being designed to support the deck, or the end of the plate may be turned upwardly with extensions such as those hereafter referred to thereby forming a continuous 85

combing. The upper end of the plate may, however, be bent to any other cross-sectional outline. As applied to the formation of the bows two suitably shaped plates are 90 employed such as shown in Fig. 2 each forming one side of the said bow and provided with flanges *a*¹ upon all their edges. The stern sections are shaped as shown in

Fig. 3 an end plate such as *b* being provided. 95

In constructing the barge the various sections are assembled with the flanges *a*¹ abutting and may be temporarily or permanently connected by means of bolts or when 100

- connected the abutting surfaces may be 65
welded together the flanges forming re-
spectively the ribs, keelson and deck string-
ers. In order to strengthen the keelson
5 at the point where the ribs meet a hollow
cross or T-shaped body such as b^1 Fig. 11,
may be provided designed to straddle the
flanges and which may be bolted or other-
wise secured thereto.
- 10 In order to increase the beam, without
altering the dimensions of the sections rec-
tangular shaped stampings or forgings,
such as c , shown in Fig. 4, may be em-
ployed and which stampings or forgings are
15 placed between the lower ends of the sec-
tions, the flanges thereof being secured to
the flanges of the said sections thereby form-
ing a double keelson. The length of the
parts c is equal to the width of the sections
20 and said plates or the like have marginal
flanges similar to flanges a^1 .

The sections may either be arranged in
alignment upon the opposite sides of the
vessel or they may be arranged so that they
25 are staggered.

According to the modification shown in Figs.
5 and 6 the end of each plate is cut away as
shown at c'' leaving an extension c^1 extend-
ing from one side of the plate to the centre
30 of said plate or thereabouts. The plates are
provided with flanges a^1 and when assem-
bled the projections of the plates upon one
side engage the cut away portions of the
35 plates upon the other side as shown in Fig.
6. The plates may be in two parts the meet-
ing ends of the plates being cut away and
flanged as just described.

Preferably the side flanges are increased
40 in width for the purpose of increasing the
strength of the ribs at the point z .

In order to increase the beam, plates may
be employed as shown by the dotted lines d
45 in Fig. 5 said plates being shaped as shown
and being inserted between the ends of the
plates.

Instead of being rectangular the ends of
the plates may be of V-shaped outline, as
shown in Figs. 7 and 8, said plates having
all round them flanges a^1 .

50 In order to increase the beam, quadri-
lateral or triangular plates, as shown in
Fig. 9, flanged upon all sides may be em-
ployed said plates being arranged as shown
55 in Fig. 10. Angle or other bars, such as
shown by the dotted lines e may be em-
ployed.

A similar arrangement may be employed
where the plates are made in two parts, as
shown in Fig. 7.

60 In Fig. 12 there is shown a plate designed
to be used as part of the structure or for in-
creasing the beam of the vessel.

This plate, which is of any suitable
width, has a corrugation or depression y

running longitudinally (when assembled) 65
through its centre. The width of the corru-
gation may be approximately half the
length of the side of the plate and it may be
of any suitable depth.

This plate, when assembled, forms, by 70
means of its corrugation, a scupper running
throughout the entire length of the hull,
greatly facilitating drainage. This corru-
gation or depression forms, when the plates
are assembled, a keelson which gives rigid- 75
ity and strength to the structure.

Other and smaller corrugations may be
provided for strengthening purposes as
shown by the dotted lines z , z^1 .

In order to secure greater strength the 80
plates may be provided with tongues adapt-
ed to overlap the adjacent surface of the ad-
joining plate or engage recesses or inden-
tations in the flanges. Tongues such as
those just referred to are shown by dotted 85
lines u in Fig. 1.

It is obvious that various modifications
may be made both in the shape of the ends
of the plates and in the manner in which
they are assembled. The upper ends of the 90
plates may, moreover, be so bent as to form
scuppers.

Claims:

1. A ship hull section consisting of a metal
plate shaped to form a side section and hav- 95
ing its lower end directed inwardly to form
a bottom portion and its upper end directed
inwardly to form a deck supporting portion,
said plate having a continuous peripheral
flange extending inwardly of the hull. 100

2. A ship hull section consisting of a metal
plate shaped to form a side section and hav-
ing its lower end directed inwardly to form
a bottom portion and its upper end directed
inwardly to form a deck supporting portion, 105
said plate having a continuous peripheral
flange extending inwardly of the hull, the
flange at the inner end of the deck support-
ing portion being provided with a lip ex-
tending inwardly of the ship whereon the 110
side edge portion of the deck may rest.

3. A ship hull section consisting of a metal
plate shaped to form a side section and hav- 115
ing its lower end directed inwardly to form
a bottom portion and its upper end directed
inwardly to form a deck supporting portion,
said plate having a continuous peripheral
flange extending inwardly of the hull, said 120
bottom portion having its inner end shaped
to provide a tongue extending adjacent a
similar tongue on the opposite plate.

4. A ship hull section consisting of a metal
plate shaped to form a side section and hav-
ing its lower end directed inwardly to form
a bottom portion and its upper end directed 125
inwardly to form a deck supporting portion,
said plate having a continuous peripheral
flange extending inwardly of the hull, said

bottom portion having its inner end shaped to provide a tongue extending adjacent a similar tongue on the opposite plate, the flange at the inner end of the deck supporting portion being provided with a lip extending inwardly of the ship whereon the side edge portion of the deck may rest.

5. In ship hull construction including a set of plates having peripheral flanges grouped 10 with an angle of each plate at a common point, and a securing member having chan-

nelled arms radiating from said point and engaging the flanges of adjacent plates.

In testimony whereof we have hereunto set our hands and affixed our seals in the 15 presence of two witnesses.

FRED. S. CROSSLEY.
F. W. CROSSLEY.

Witnesses:

PATRICK J. CRUMP,
MARY C. TULLY.
